LIGHTING FIXTURE GLOBE

Robert H. Ensign, Bronxville, N. Y., assignor to The Phoenix Glass Company, Monaca, Pa., a corporation of West Virginia

Application May 13, 1954, Serial No. 30,464

Term of patent 7 years

(Cl. D48—16)

FIG. 1.

FIG. 2.

FIG. 3.

To all whom it may concern:

Be it known that I, Robert H. Ensign, have invented a new, original, and ornamental Design for a Lighting Fixture Globe, of which the following is a specification, reference being had to the accompanying drawing, forming a part hereof.

Fig. 1 is a top plan view of a lighting fixture globe showing my new design, the portion shown in broken lines being the same as that shown in solid lines;

Fig. 2 is a side elevational view thereof, partly broken away and in section.

Fig. 3 is a bottom plan view.

I claim:

The ornamental design for a lighting fixture globe, as shown and described.
